CARD SORTING DEVICE

Roger Connor, Athens, Ohio, assignor to The
McBee Company, Athens, Ohio, a corporation

Application April 3, 1944, Serial No. 529,378

4 Claims. (Cl. 129—16.1)

1

This invention relates to devices for selectively sorting cards of the type widely known commercially as "Keysort" cards.

Cards of the type referred to are provided along one or more edges with one or more rows of perforations which are grouped and identified by suitable indicia to represent desired classifications.

In practice, a plurality of these perforations are notched or slotted out to the edge of the card, forming a pattern of notches or slots pertaining to a single classification. The cards when thus notched or slotted may be selectively sorted by passing one or more sorting rods through the selected perforations of a group of cards, which perforations representing the desired classification. By then elevating the sorting rod or rods, the cards having notches or slots coinciding with the perforations penetrated by the rod or rods will disengage from the rods, while the remainder of the cards will remain suspended from the rod or rods. Thus, the cards of one or more selected classifications are sorted from a stack of cards.

It is the principal object of my present invention to provide an improved sorting device for such cards to enable sorting of a relatively small number of cards from a great number thereof to be accomplished more expeditiously than heretofore.

One form which the invention may assume is exemplified in the following description and illustrated by way of example in the accompanying drawings, in which:

Fig. 1 is a perspective view of a card sorting device embodying the preferred form of my invention, shown in the position to receive the cards for sorting.

Fig. 2 is a perspective view of my card sorting device shown in the position it assumes when the sorted cards are disengaged from the remainder of the stack of cards.

Fig. 3 is an end elevation of my card sorting device, showing it in the position it assumes when sorted cards are disengaged from the remainder of the stack.

Fig. 4 is a similar view partly broken away, showing the device in the position which it assumes to receive cards for sorting.

Fig. 5 is a fragmentary view in perspective of the selector rod holder of the device.

Referring more particularly to the accompanying drawings, 10 indicates a selective sorting device for cards of the character commercially known as "Keysort" cards. These cards, as previously set forth, are edge-punched cards, the

5 punchings of which are notched out to the edge in patterns to represent a desired classification. The card sorting device 10 is what is known as a selective sorting device by means of which punched and notched cards of one or more selected classifications may be separated from a stack of cards. The sorting device 10 is of a construction, size and weight that it is portable and may be ordinarily disposed on a desk or table top for use.

10 The device 10 is composed of a rigid frame 11 having suspended therein a rotatable card receiving tray 12. The frame 11 is formed of a flat base 14 of dimensions sufficient to properly support the device 10 on a desk or table top. At one end of the base and extending vertically therefrom is an end frame 15 to which the card receiving tray 12 is rotatably connected for rotation in a vertical plane about a horizontal axis, as will be described.

15 The card receiving tray 12 comprises a flat bottom plate 16 having large openings 17 formed therein. At one end of the bottom plate 16 is a vertically extending end plate 18 which is disposed adjacent to and in parallelism with the end frame 15 of the frame 11. A pintle 19 extends horizontally between the end frame 15 and the end plate 18 of the tray 12 to rotatably connect the same and thereby rotatably suspend the 20 card receiving tray 12 within the frame 11, so that it may revolve in a vertical plane about a horizontal axis. At the front end of the bottom plate 16 is a vertically extending aligning plate 20, extending, of course, at right angles to the 25 end plate 18. The end plate 18 and the aligning plate 20 do, of course, extend at right angles to the face of the bottom plate 16.

30 It is intended, as illustrated, to position a stack of cards to be sorted in the tray in parallelism with the end plate 18 with the front ends of the cards abutting the aligning plate 20. Such abutment will cause proper relative alignment of the cards and proper alignment of the perforations or punchings therein with the end plate 35 18 and a selector rod guide 21. This selector rod guide 21 is disposed at the end of the bottom plate 16 opposite the end plate 18 in parallelism with the latter, and it is composed, as illustrated, of two spaced but parallel plates 22. 40 The selector rod guide 21 is formed with a plurality of perforations 23 so disposed relative to the face of the bottom plate 16 and the aligning plate 20 that they will register with the perforations in the cards of the stack disposed in the tray 45 12. That is to say, the perforations 23 in the 50

selector rod guide 21 are complementary to the perforations of cards to be sorted in the tray 12. The end plate 18 is formed with similar perforations 24 which are likewise disposed so as to be complementary to and register with the perforations in the cards to be sorted, when the latter are disposed in the tray 12, as previously described.

Thus, it is seen that when cards A are disposed in the tray 12 in parallelism with the end plate 18 and with their ends abutted against the aligning plate 20, that the perforations in the cards in the end plate 18 and in the selector rod guide 21 will be in register so that one or more selector rods 25 may be projected through the selector rod guide 21, the cards and the end plate 18. When selector rods are so projected or positioned, they will be supported at one end, of course, by the selector rod guide 21 and at the other end by the end plate 18.

To properly manipulate the selector rods 25 and to maintain them in a selected pattern for sorting, I provide a selector rod holder 26, which is more clearly illustrated in Fig. 5 of the drawings. This selector rod holder 26 comprises an elongated member 27, which is perforated complementary to the selector rod guide 21 and, consequently, to the cards to be sorted. Further, the member 27 is at all times in alignment with the selector rod guide 21 and is perforated in identically the same fashion with the perforations in longitudinal alignment.

The selector rods 25 are provided with enlarged heads 28 which will not pass through the perforations in the member 27. Therefore, the selector rods 25 may be projected endwise through the member 27 and into the corresponding perforations in the selector rod guide 21, the spacing and positioning of the selector rods 25 being, of course, determined by the selected classification.

To maintain the selector rods 25 from endwise movement a hinged cover plate 29 is fitted to the selector rod holder 26 so that after the rods have been positioned, this cover plate 29 may be disposed as illustrated in Figs. 1 and 2 to prevent endwise movement of the selector rods by clamping the heads 28 thereof to the face of the member 27.

The selector rod holder 26 is connected by two telescoping slides 30 to the bottom of the card receiving tray 12. These telescoping and guiding slides 30 extend longitudinally of the card receiving tray 12 and enable the selector rod holder 26 to be moved longitudinally relative to the tray 12. The amount of movement permitted the selector rod holder 26 is sufficient to enable the selector rods 25 to project entirely through a stack of cards disposed in the tray 12 and into the end plate 18 and to be completely disengaged from such stack of cards upon opposite movement. The construction of the telescoping slides 30 is conventional and for this reason their construction is not further illustrated or described.

It is desirable to aid in the alignment of the cards that the card receiving tray 12 be disposed at an acute angle to the horizontal when in card receiving position, as shown in Fig. 4. For this reason a stop member 31 is fitted to the end frame 15 at a point that it will be engaged by the top edge of the end plate 18 of the tray 12, as illustrated in Figs. 1 and 4, when the tray 12 is in card receiving position. Also, the end plate 18 is fitted with an arcuate latch plate 32 which is fastened

to the end plate 18 concentric to the pintle 19. A latch finger 33 is fitted to the top of the end frame member 15 to engage a notch 34 in the latch plate 32, when the card receiving tray 12 is in the card receiving position. The construction of the latch finger 33 and the notch 34 is such that disengagement may be readily effected when desired by merely grasping the card receiving tray and revolving it in a clockwise direction as it appears in Fig. 4.

The position of the stop member 31 is such that when the card receiving tray 12 is inverted to disengage the selected cards from the remainder of the stack, the opposite end of the edge plate 18 will abut against the member 31, as illustrated in Fig. 3. If desired, a slight jarring action may be produced by impacting the end plate 18 against the member 31, when the parts are in the position shown in Fig. 3. I also desire to point out that the openings 17 in the bottom plate 16 enable the operator to manually manipulate the cards, if found necessary or desirable.

In operation of the device, it is constructed and assembled substantially as illustrated and described, and when it is desired to sort cards, the selector rod holder is withdrawn, as shown in Fig. 1, and the cover plate 29 upraised to expose the perforations in the member 27 of the holder 26. Selector rods 25 may then be inserted through the selected perforations to form a pattern agreeing with the pattern necessary to select desired classifications from the cards to be sorted. The cover plate 29 is then repositioned to latch the selector rods 25 to the selector rod holder 26. The cards A to be sorted are then inserted in the tray 12 against the end plate 18 and with their ends abutting against the aligning plate 20. Thus, the cards A will extend transversely of the card receiving tray with the perforations along their lower edge registering with the perforations in the end plate 18, the selector rod guide 21 and the selector rod holder 26.

When the cards are so disposed in the tray, the selector rod holder is moved longitudinally of the tray in a direction causing the selector rods 25 to penetrate through the selected perforations in the stack of cards in the tray and then penetrate into the end plate 18. The operator then revolves the tray 12 about the pintle 19 to the position shown in Fig. 3, at which time those cards B having notches aligned with the perforations through which the selector rods 25 project will drop from the stack and tray and deposit on the base plate 14 in the frame 11, as shown in Fig. 3. The remaining cards in the stack, of course, will be held suspended in the tray by the selector rods 25. The operator then removes the cards B which have dropped or have been selected from the stack from the frame and returns the tray to the starting position, as illustrated in Fig. 4. At this point the operator moves the selector rod holder 26 to the left and longitudinally of the tray 12, disengaging the selector rods 25 from the remainder of the cards A in the stack, permitting those cards to be removed.

The operation just described is then repeated on succeeding stacks or batches of cards until they have been all sorted. Obviously, any desired classification or classifications may be selected by merely changing the positions of the selector rods 25 to correspond with the desired classification or classifications.

From the foregoing it is obvious that I have provided a comparatively simple device for selectively sorting cards of the type known commer-

cially as "Keysort" cards. It will be apparent from the foregoing and from the drawings that by means of my improved device selective sorting of a relatively few of a large stack of cards may be rapidly and accurately accomplished in a comparatively short time.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. In a card sorting device, an L-shaped frame consisting of a horizontally disposed base and a vertically disposed support member, a tray pivoted to the said support member for rotation about a horizontal axis, cooperating means on the frame and tray whereby the latter is limited to clockwise and counterclockwise rotational movement approximately 180 degrees between two different positions with respect to the frame, a selector rod guide on the tray, a plurality of sorting rods guided in said guide for movement in a direction parallel to the axis of rotation of the tray, a holder removably connected with said sorting rods, and telescopic connections between said holder and the tray to enable movement of the holder in a direction parallel to the direction of movement of the sorting rods.

2. In a card sorting device, an L-shaped frame consisting of a horizontally disposed base and a vertically disposed support member, a tray consisting of an open frame base, an end wall and a side wall, said tray being pivoted to the support member for rotation about a horizontal axis, cooperating means on the frame and tray whereby the latter is limited to clockwise and counterclockwise rotational movement between two different positions with respect to the frame, a selector rod guide on the tray, a plurality of sorting rods guided in said guide for movement in a direction parallel to the axis of rotation of the tray, a holder removably connected with said sorting rods, and telescopic connections between said holder and the tray to enable movement of the holder in a direction parallel to the direction of movement of the sorting rods.

3. In a card sorting device, an L-shaped frame consisting of a horizontally disposed frame consisting of a horizontally disposed base and a vertically disposed support member, a tray consisting of an open-frame base, an end wall and a

side wall, said side wall being pivoted to the support member whereby the tray is rotatable on a horizontal axis in relation to the frame, cooperating means on the frame and tray whereby the latter is limited to clockwise and counter-clockwise rotational movement between two different positions with respect to the frame, a selector rod guide on the tray, a plurality of sorting rods guided in said guide for movement in a direction parallel to the axis of rotation of the tray, a holder removably connected with said sorting rods, and telescopic connections between said holder and the tray to enable movement of the holder in a direction parallel to the direction of movement of the sorting rods.

4. In a card sorting device, an L-shaped frame consisting of a horizontally disposed frame consisting of a horizontally disposed base and a vertically disposed support member, a tray consisting of an open-frame base, an end wall and a side wall, said side wall being pivoted to the support member whereby the tray is rotatable on a horizontal axis in relation to the frame, cooperating means on the frame and tray whereby the latter is limited to clockwise and counterclockwise rotational movement between two different positions with respect to the frame, a selector rod guide mounted on said open-frame base, a plurality of sorting rods guided in said guide for movement in a direction parallel to the axis of rotation of the tray, a holder removably connected with said sorting rods, and telescopic connections between said holder and the tray to enable movement of the holder in a direction parallel to the direction of movement of the sorting rods.

ROGER CONNOR.
